APPARATUS FOR OBTAINING AEROSOLS

Lucien Dautrebande, Washington, D. C., assignor
to Aerosol Corporation of America, New York,
N. Y., a corporation of Delaware

Application July 27, 1948, Serial No. 40,947

4 Claims. (Cl. 261—21)

1

This invention relates to methods and apparatus for obtaining improved aerosols of relatively high stability by obligatory filtration through a turbulent body of liquid, and especially to aerosols of a mean particle size (diameter) of not over about 0.5 micron.

In aerosol therapy, it is very important to obtain aerosols of very low particle size if it is desired to have the aerosol penetrate to the innermost passages or zones in the lungs (alveoli). For this purpose, aerosols of not over 0.5 micron mean particle size are to be preferred, and in general the aerosols should be substantially free of particles of more than 1 micron diameter. The larger aerosol particles attract the smaller ones, they tend to deposit in the nasal and throat passages, and in some instances such deposit leads either to serious difficulties or to a lack of effectiveness of the substances dispersed.

In accordance with the invention, it has been found that aerosols of a mean particle size of not over 0.5 micron may be obtained readily by means of a convenient apparatus.

One of the objects of the invention is to produce improved aerosols having a mean particle size of not over 0.5 micron. Another object of the invention is the provision of apparatus for obtaining improved aerosols. Other objects of the invention will be apparent as details or embodiments of the invention are set forth hereinafter.

In accordance with the invention, a liquid is dispersed by means of a compressed gas, such as air, to form a cloud containing both stable and unstable dispersed liquid particles in the gas, and the cloud is impelled upwardly and passed through a series of turbulent bodies of liquid, e. g., three, then directed onto a liquid film layer or baffle, then passed through a liquid film barrier supported upon an apertured or foraminous member, and then preferably passed downwardly into and up through a body of liquid under agitation. The resulting aerosol has a mean particle size of not over 0.5 micron, e. g., from an aqueous solution regardless of the molecular weight and concentration of solute within the usual concentration ranges suitable for aerosol therapy, e. g., 1 to 10% by weight of the therapeutic agent.

Referring to the drawing, Figure 1 diagram-

2

matically illustrates an apparatus suitable for carrying out the method of the invention, partially in elevation, partially in section and partially fragmentary.

Figure 2 shows a cross-sectional view along the lines 2—2 in Figure 1, and shows the three sets of jet apertures in air inlet tube 3 and in the liquid delivery tube 4.

Figure 3 illustrates an alternate aerosol conduit member 6A; and also an optional baffle attachment which may be used with member 6 or 6A.

The vessel 1 is provided with a liquid reservoir, which may be detachably connected, e. g., by screw threads, for holding the liquid to be dispersed 5, a jet member made up of air inlet 3 and liquid supply tube 4 which extends into the liquid to be dispersed. An aerosol conduit member 6 having a series of alternate constricted cross-sectional zones is suitably and preferably adjustably supported substantially vertically over and directly in the path of the aerosol cloud formed at zone 2. Member 6 may be provided with a detachable funnel shaped extension 6C, if desired. Optional cylindrical screen member 8 surrounds the member 6. A hood member 7 having a closed top, apertured sidewall, and an enlarged lip lower portion is set over and around the member 6. The lip and suitable support members of 7 fit snugly in the vessel 1, so that the position of member 7 may be slidably adjusted. Member 7 divides vessel 1 into an upper zone and a lower zone. Aerosol delivery tubes 11 and 14 communicate with vessel 1, and may lead directly to an aerosol storage chamber; but preferably lead into vessel 12 near the bottom thereof. Tube 15 connects vessel 12 with the aerosol storage chamber 16.

If desired, there may be provided one or more optional liquid supply tubes 7a and one or more optional drain tubes 1b. Water or another liquid may be introduced through 7a, and it will flow over and down around member 7, so as to form a continuous film, and then out through 1b, situated just above the lip portion of member 7. Member 7 may be suitably formed so that this liquid will not flow into the lower zone, e. g., with the upper part of each opening set outwardly from the lower part. The openings in

member 7 may be arranged in gutter-like grooves in which the liquid flows.

If desired, the liquid reservoir in vessel 1 may have a conical shaped bottom, or be provided with a suitable feeding device for maintaining constant level of liquid therein, or it may be provided with means for continually removing liquid therefrom and replacing it with solution of controlled concentration.

In operation, compressed air or other suitable gas is introduced in tube 3, under such conditions that liquid will be drawn up through tube 4 and dispersed in the form of a cloud or a mist at zone 2 and impelled upwardly into the member 6. The conditions are selected so that the cloud contains both relatively stable and unstable particles, and the latter will condense or deposit in tube 6 and form very turbulent bodies of liquid at the constricted zones thereof. These liquid bodies are maintained in dynamic equilibrium, e. g., by balancing the amount of liquid supplied against the amount running downward therefrom. Relatively more stable aerosol particles can traverse these turbulent liquid areas. The mist or cloud leaving member 6 is directed onto the lower surface of the top of member 7, where unstable liquid particles therein coalesce and form a liquid layer which may flow downwardly along member 8 or the apertured sidewall 7 or both. Then the mist or cloud passes through member 8 and the apertured sidewalls of member 7, where unstable liquid particles may coalesce and form continuous liquid layers, into zone 10 and then through tubes 11 and 14 into the body of liquid 13. Under the preferred conditions, the rate of flow of gas is such that the liquid 13 is maintained under very vigorous agitation thereby. Then the resulting improved aerosols pass through tube 15 into chamber 16.

The apparatus or parts thereof may be made of glass, metal, plastic, or the like suitable material; and although various members are described as being substantially circular in cross section, other shapes may be used provided the critical relationships disclosed are retained. The member 6 may be made up of sections of glass tubing joined by rubber tubing, or all of glass, metal, etc. A two liter Erlenmeyer flask is suitable as vessel 12 in view of its inclined conical wall section. However, for commercial purposes vessels 1 and 12 may be built as sections of a single unitary apparatus having appropriate partitions. Preferably the mean inner diameter at the constrictions of member 6 is of the order of 0.6 to 1.0 cm., preferably proportional to the air flow rate as discussed hereinafter; and the mean inner diameter of the bulb or enlarged sections of member 6 is from 25% to 100% greater than that of the constricted sections. Generally, the length of each constricted section in member 6 should be such as to provide a turbulent liquid body at least about 1 cm. deep, up to about 4 cm., preferably a total of at least 3 cm. of turbulent liquid through which the aerosol particles must pass. This turbulent mass has been found to be effective in facilitating the production of aerosols of the desirable uniformly small size. A possible explanation may be the fact that the turbulence creates a myriad of liquid films through which the aerosol must pass, each of which assists in the production of the unique aerosols described herein as resulting from the use of the preferred conditions of my method and construction of my apparatus. The distance between the barriers in member 6, i. e., the lengths of the enlarged por-

tions, is not very critical, as long as the liquid barriers are maintained. The lower portion of member 6 may be set very closely over zone 2, but it is preferred that there be a distance of 3 to 4 cm. between the apertures of member 3 and the first liquid barrier constricted zone in member 6. Generally, the distance between the top of member 6 and the top of member 7 is in the range of 5 to 9 cm., preferably proportional to the air flow as described hereinafter.

In vessel 12 the aerosol is preferably introduced at a depth in the range of 2 to 6 cm. below the liquid surface. The cross-sectional area at the surface of the liquid should be in the range of 20 to 50 times that of the aerosol inlet tube, so as to provide a sudden decrease in velocity of the aerosols.

The jet member may have one, two or three sets of air and liquid apertures, three being shown in the drawings.

In general, the size of the apertures may be such as to deliver an air flow per aperture in the range of 15 to 25 liters per minute, for conventional relatively low air pressures of the order of 7 to 55 pounds per square inch gauge. For this air flow, the rate of dispersion of liquid per aperture is preferably 10 to 20 cc. per hour.

In a typical example, a 1% aqueous eosin solution is dispersed as aerosols of mean particle size of 0.43 micron, using the apparatus illustrated in Figure 1, and an air input of 28 pounds per square inch gauge. Substantially all the particles are less than 1 micron average diameter. The particle size of the aerosols is determined by passing the aerosols into a chamber, e. g., of 225 cubic meters capacity, the interior of which is maintained at atmospheric pressure. After dispersion for 10 minutes, the aerosols are allowed to settle on collector plates, coated with a thin film of petrolatum, e. g., for an hour, then the plates are protected by a cover, cemented at the edges, e. g., with Duco cement, and immediately examined by means of an oil immersion microscope, e. g., 1125 magnification.

Alternatively, the particle size may be determined by nephelometric methods or by electron microscope means. In the latter method, there are observed aerosol particles which are too small to be seen by means of the optical microscope, and when these are taken into consideration, the mean particle size of the aerosol will be even smaller (0.07 micron, mean size, as determined after collecting freezing and drying).

Under similar conditions, a 10% aqueous solution of eosin gives aerosols having a mean particle size of 0.49 micron.

Similar results are obtained using aqueous solutions of materials of different molecular weights. It is an advantage of the invention that, regardless of the type or molecular weight of the solute material or of the concentration thereof within suitable therapeutic ranges, e. g., 1 to 10%, that aerosols of less than 0.5 micron mean diameter may be obtained, and most of these will fall within the range of 0.3 to 0.5 microns.

Passing the resulting aerosols from vessel 12 into a second or serially into two more such vessels with distilled water therein did not show any color change. This indicates that liquid 13 just about completely removed all unstable eosin solution, red colored particles.

If desired, the vessel 12 and body of liquid 13 may be eliminated, in which case the particle size will vary with the concentration of the solute but will never exceed 0.8 micron (mean size). Al-

ternatively, the vessel 12 may be used but the body of liquid 13 may be eliminated, in which case the particle size will vary with the concentration of the solute but will never exceed 0.68 micron (means size). These results indicate that the vessel 12 alone will remove some of the larger particles, and that liquid 13 removes more of the larger particles.

In the above examples, the body of liquid 13 in vessel 12 is the same as that of liquid 5 in vessel 1. Other liquids may be used in vessel 13, e. g., a light mineral oil, such as kerosene, aqueous solutions of glycerol, glycols, or the like.

The particular jet members discussed above are admirably adapted for producing aerosols. However, other types of jet members may be used, as known in the art, provided the resulting mist or cloud contains both very fine and stable liquid particles and also a substantial amount of larger relatively unstable particles. The unstable particles will tend to be removed in the turbulent liquid body, or in the treatments subsequent to contact with the turbulent body, or both. If desired, the liquid to be dispersed may be fed under positive pressure or at atmospheric pressure directly into tube 4, e. g., from an outside supply through suitable connections, not shown. This prevents an increase in the concentration of the solution being dispersed during the dispersion.

A plurality of jet members and aerosol conduit members may be used, if desired.

If desired, the upper end of member 6 may be completely closed or partially closed, e. g., by a stopper with a small opening, and very efficient elimination of larger particles will result, but at a decreased rate of output.

The relatively uniform aerosols of very low mean particle size, having substantially all particles of less than 1 micron maximum size, are particularly suitable for use in aerosol therapy, especially in the treatment of the innermost passages or regions (alveoli) in the lungs. If it is desired to simultaneously treat or medicate the nasal or throat passages, larger mean particle size aerosols, having some particles of the order of 1 to 5 microns diameter, may be included. Such aerosols may be produced in the present apparatus by attaching member 6B at the lower end of member 6 or 6A.

The aerosols produced in accordance with the invention may be suitable for other uses, e. g., precipitation or agglutination of very fine dust particles; which dust particles are so fine that they pass through a liquid layer, through the nasal and throat passages, and into the innermost regions of the lungs where they may deposit and produce very undesirable effects, e. g., silicosis. The very fine aerosol particles tend to agglomerate and coalesce with the very fine dust particles, to produce larger size individual particles and to produce dust aggregation which settle down more quickly and do not penetrate further than the upper respiratory passages.

In view of the foregoing disclosures, variations and modifications thereof will be apparent to those skilled in the art, and all such variations and modifications are broadly contemplated within the invention.

I claim:

1. In an apparatus for producing an improved aerosol, a vessel provided with atomizing means comprising a liquid feed tube in communication with a liquid supply and an upwardly directed air inlet tube, a conduit member having three

alternate constricted cross-sectional zones set axially about vertically above said atomizing means and adapted to assist in forming and supporting a turbulent liquid body, a hood member set around and over said conduit member, said hood member having a closed top and apertured sidewalls and said hood member dividing said vessel into two zones, and an aerosol outlet tube, the mean inner diameter at the constrictions of said conduit member being in the range of 0.6 to 1.0 cm. and the mean inner diameter of the enlarged sections of said conduit member being in the range of 25 to 100% greater than the diameter at the constrictions.

2. In an apparatus for producing an improved aerosol, a vessel provided with a liquid reservoir, atomizing means comprising a liquid feed tube in communication with the said reservoir and an upwardly directed air inlet tube, a conduit member having three alternate constricted cross-sectional zones set axially about vertically above said atomizing means and adapted to assist in forming and supporting a turbulent liquid body, a hood member set around and over said conduit member, said hood member having a closed top and apertured sidewalls and said hood member dividing said vessel into two zones, means for introducing liquid on to the top of said hood member and liquid outlet means near the bottom of said hood member, and an aerosol outlet tube, the mean inner diameter of the constrictions of said conduit member being in the range of 0.6 to 1.0 cm. and the mean inner diameter of the enlarged sections of said conduit member being in the range of 25 to 100% greater than the diameter at the constrictions.

3. In an apparatus for producing an improved aerosol, a vessel provided with a liquid reservoir, atomizing means comprising a liquid feed tube in communication with the said reservoir and an upwardly directed air inlet tube, a conduit member having a plurality of alternate constricted cross-sectional zones set axially about vertically above said atomizing means and adapted to assist in forming and supporting a turbulent liquid body, a hood member set around and over said conduit member, said hood member having a closed top and apertured sidewalls and said hood member dividing said vessel into two zones, a tube member leading from the upper zone of said vessel to near the bottom of a liquid reservoir in a second vessel, and an aerosol outlet tube, the mean inner diameter at the constrictions of said conduit member being in the range of 0.6 to 1.0 cm. and the mean inner diameter of the enlarged sections of said conduit member being in the range of 25 to 100% greater than the diameter at the constrictions.

4. In an apparatus for producing an improved aerosol, a vessel provided with a liquid reservoir, atomizing means comprising a liquid feed tube in communication with the said reservoir and an upwardly directed air inlet tube, a conduit member having a plurality of alternate constricted cross-sectional zones set axially about vertically above said atomizing means and adapted to assist in forming and supporting a turbulent liquid body, a hood member set around and over said conduit member, said hood member having a closed top and apertured sidewalls and said hood member dividing said vessel into two zones, a tube member leading from the upper zone of said vessel to near the bottom of a liquid reservoir in a second vessel conical in form, and an aerosol outlet tube, the mean inner diameter at the con-

strictions of said conduit member being in the range of 0.6 to 1.0 cm. and the mean inner diameter of the enlarged sections of said conduit member being in the range of 25 to 100% greater than the diameter at the constrictions.
